(57) **CLAIM**

The ornamental design for a baby crib, as shown and described.

DESCRIPTION

FIG. 1 is a top, front, right side perspective view of a baby crib showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, front, right side perspective view of the baby crib showing in an environment in which it may be used; and,

FIG. 9 is a top, front, right side perspective view of the baby crib showing in another environment in which it may be used.

The deemphasized lightened portions surrounded by broken lines and the broken lines representing the boundary are for environmental and illustrative purposes only and form no part of the claim.

1 Claim, 9 Drawing Sheets
